(57) **CLAIM**

The ornamental design for a outdoor lawn landscape lamp, as shown and described.

DESCRIPTION

FIG. 1 is a front elevational view of a outdoor lawn landscape lamp showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The broken lines shown in drawings are for the purpose of illustrating portions of the outdoor lawn landscape lamp and form no part of the claimed design.
